(57) **CLAIM**

I claim the ornamental design for a charging hub bridge, as shown and described.

DESCRIPTION

FIG. 1 is a front-bottom-left side perspective view of a charging hub bridge of my new design;

FIG. 2 is a back-top-right side perspective view thereof;

FIG. 3 is a front elevation view thereof;

FIG. 4 is a back elevation view thereof;

FIG. 5 is a bottom plan view thereof;

FIG. 6 is a top plan view thereof; and,

FIG. 7 is a right-side elevation view thereof.

The broken lines shown in the drawings are for the purpose of illustrating elements of the charging hub bridge that form no part of the claimed design.
